UNITED STATES PATENT OFFICE.

SALVE NELSON HOWESTOLL, OF BROOKLYN, NEW YORK.

DESIGN FOR A TABLE-KNIFE.

SPECIFICATION forming part of Design No. 25,988, dated September 8, 1896.

Application filed December 24, 1895. Serial No. 573,233. Term of patent 7 years.

To all whom it may concern:

Be it known that I, SALVE NELSON HOWESTOLL, a citizen of the United States, residing at Brooklyn, in the county of Kings and State of New York, have invented and produced a new and original Design for Table-Knives, of which the following is a specification, reference being had to the accompanying drawing, forming part thereof, in which the figure of the drawing illustrates my original design.

The leading feature of my design consists in the blade A, the end a^1 of which is rounded, the outer portion of which blade is flattened and flared laterally, from which flared portion the blade tapers to a restricted shank portion a^2 and is joined to the handle at a^3 , but one side or edge of the blade is curved more than the other side, thus giving the flared end of the blade a curved or inclined direction, and the handle B tapers outwardly in a uniform degree, and the end of the handle is rounded or semicircular in form, and I also ornament the side or sides of the handle with a band near the connection of the handle and the blade, adjacent to which band or imitation band is formed an ornamentation, and in

the central portion of the handle is formed an ornamental design or embellishment of the representation of a shield, from which extends a handle or projection, said shield having across the face thereof an obliquely-directed band or strip, and between this shield and the end of the handle is formed additional ornamentation of two portions, between which extends an upwardly-directed spray, all as shown in the drawing.

It will be seen that the original design herein produced is ornamental and symmetrical and produces a pleasing and attractive figure.

Having described my new and original design, I claim and desire to secure by Letters Patent—

The design for knives, substantially as herein shown and described.

In testimony that I claim the foregoing as my invention I have signed my name, in presence of the subscribing witnesses, this 18th day of December, 1895.

SALVE NELSON HOWESTOLL.

Witnesses:

C. GERST,
L. M. MULLER.
